1

This invention relates to direct current hoist magnetic controllers for electric overhead travelling cranes.

Requirements of hoist motions for cranes powered with series wound direct current motors and series wound solenoid brakes are such that the motion always requires power from the motor for hoisting, while it may require either motoring torque for lowering an empty hook and light loads, or dynamic braking torque when lowering heavy overhauling loads. The electrical control should also have maximum flexibility so that it can be easily adjusted to suit the requirements of the crane on which it is installed.

For the hoisting duty, the controller connects the motor to the power lines with the motor-armature, the motor series field, the operating series coil of the electro-mechanical brake, and the speed accelerating resistances in an electrically series connected circuit. Increasing values of speed and torque are obtained by decreasing the amount of resistance in series with the motor. On the final point, the motor gets connected directly across the power lines as a straight series connected motor.

For the lowering duty, the connections are so made that the motor is converted into a shunt motor by putting the motor series field across the line with resistance in series connection and the whole connected parallel with the armature circuit, i. e., during lowering the series field circuit and the armature circuit are in parallel.

The series coil of the electromechanical brake is always connected in series with the motor field, i. e., while lowering, the brake coil always comes in the series field circuit. When thus connected, the motor develops a motoring torque if light hook load is to be handled; or dynamic braking torque if heavy loads are to be lowered. The changes from power to dynamic braking and vice versa in the lowering direction is an inherent feature of the hoist magnetic dynamic braking crane controllers, and is independent of either the operator or the functioning of the control devices.

The speeds are controlled over a master switch which has normally five control points, both in the hoisting and the lowering directions. The master switch operates the various contactors in the control panel, which then vary the resistances provided in the motor armature, the motor series field and the power line circuits. The acceleration and deceleration during lowering as well as hoisting cycles are automatically provided under the control of magnetic definite-time

2

relays. The controller has additional safety features, viz., main disconnecting line knife switches, overload relays, control knife switches and control circuit fuses. In the final notch of the master switch during lowering, the motor has maximum resistance in the series field circuit, so as to get minimum possible motor field current to get maximum lowering speeds both with light hook or heavy loads.

15 A direct current series wound mill type motor, because of its favourable torque characteristics is standardised for crane service, when the cranes are powered on direct current supply. It is however an inherent limitation of a direct current mill type series wound motor that it rebels against operation as a shunt motor with highly weakened fields as is the standard operation with crane hoist controller during lowering cycle. With weakened field, the mill type series motor 20 develops less torque when it is working as a generator to create dynamic braking action, than when it works as a motor at that current.

This is due to the effect of the armature reaction at high armature currents with weakened fields. The armature reaction tends to weaken the field in case of generator action. Thus an unstable action is set in, which becomes cumulative when once started, causing the motor to run away at enormous speeds.

30 Due to the above inherent stability limitation, the field current during lowering for a hoist controller is never reduced to below 50 per cent of its normal full load current rating. If the field current is below 50 per cent, the motor operates very near its stability limit while handling heavy loads at high speeds with reduced fields. The limitation of the field weakening at heavy load, therefore gives average speed difference of about 25 per cent between the maximum light hook 35 lowering speed and maximum full load lowering speed, the light load speed being always lower than full load speed, making the crane definitely slower in its operation.

To raise the stability limit of the series motor 45 at weakened field, the common practice with all the renowned control manufacturers is to introduce a permanent resistance step in series with the armature during lowering only. Addition of this resistance in its turn reduces the voltage impressed on the armature, and this reduces the light hook lowering speed of the hoist to a greater extent.

It is the object of this invention to design a control circuit, provided with a simple relay, 50 such that the light hook lowering speed can be

made almost as high as the full load lowering speed and at the same time increase the stability of the motor operation while handling heavy loads at high speeds.

According to this invention in the control circuit of the hoist panel, I introduce a double coiled relay, one of the coils being connected in series with a variable resistance across a resistance step in the armature loop, the other coil being connected directly across the resistance in the armature loop combined with the line resistance, i. e., (resistance common to the armature and the series field loop), said relay being adapted to control two contactors, one normally open and the other normally closed, said two contactors being adapted to control the speed regulating resistances in the armature and the series field circuits such that high lowering speeds are obtained both while lowering light hook or heavy overloads without causing any instability in the motor.

The normally open contactor is connected across a resistance step in the armature loop and the line resistance (resistance common to the armature and the series field loop).

The normally closed contactor is connected between the resistance in the armature loop and the resistance in the series field. During lowering of empty hook and the pre-set values of light loads, the normally closed contactor remains energised keeping its contacts open while the normally open contactor closes only on the high speed points of the master switch; when the normally open contactor closes, the resistances get so connected that maximum resistance is introduced in the series field circuit giving maximum speed.

With overhauling loads in the high speed points for the master switch, the normally closed contactor gets deenergised closing its contacts while the normally open contactor does not get any power and remains open, with the result that the series field of the motor is strengthened while the line resistance remains in the circuit. Thus proper dynamic braking action of the motor is obtained at the same time increasing the stability of the motor.

For a better understanding of the invention, reference may be made to the following description taken in conjunction with the accompanying drawing wherein the figure is a schematic illustration of a control system wherein the features pertaining to my invention are introduced.

In the drawing an electric motor of the direct current series type is shown provided with an armature (ARM), commutating fields (CF) and series fields (SF), which may be suitably coupled to the operating mechanism of a crane hoist. Since the construction of the crane hoist mechanism and the manner of installation of the motors, as well as that of mounting of the electro-mechanical brakes are well known, it is not deemed necessary to illustrate them. Notation (SB) denotes the series type operating coil of the electromechanical brakes which is mounted on the motor shaft extension (not shown).

A master switch (MC) which a number of cam operated contacts is provided to control the operation of the motor. The contact segment 11 is disposed to engage the contact finger 1 so that as long as the two are engaged, the contacts are closed and the circuit is made complete. Thus the contacts 2 of the master switch MC close when they are engaged to the segment 22, and so on for other contacts in sequence.

The functions of various contactors and relays are as follows:

Contactor Device	Function
M.....	Main negative line contactor, operating as a circuit breaker. Remains energised under normal condition.
H.....	Hoist directional contactor. Remains energised during hoisting only.
L.....	Lower directional contactor. Remains energized during lowering only.
1E.....	Lower series field contactor. Remains energized during lowering only.
2E.....	Dynamic braking contactor (spring closed i. e., its contacts are kept normally closed by a spring, and open when the contactor is energised).
1A.....	Armature accelerating contactor, closing on 3rd notch hoisting and 4th notch lowering with light loads.
15 2A.....	Armature accelerating contactor closing on 4th notch hoist and 3rd notch lower.
3A.....	Armature accelerating contactor closing on 5th notch hoist and 4th notch lower.
1FA.....	1st Field accelerating contactor opens on 3rd notch lower; remains always energized in the "Off" position, as well as during hoisting.
20 2FA.....	2nd field acceleration contactor, opens on 4th notch lower; remains energized in the "Off" position, as well as during hoisting.
3FA.....	3rd field accelerating contactor, opens on 5th notch lower; remains energized in "Off" position and during hoisting.
4FA.....	Field accelerating contactor; spring closed; remains always energized, except when lowering overhauling loads. Contacts close on the 4th notch when 1A contactor does not go in.

FUNCTION AND SETTING OF THE RELAYS

30 *Relay CR—Magnetic time control relay*

This relay controls acceleration during hoisting and lowering under both normal loads and overloads. It provides adjustable definite time in energizing the contactor 2A. It is controlled over the master switch contacts 7. Its coil is kept energised in the "off" position of the master switch. It is deenergized on 4th notch hoist and 3rd notch lower. When the relay opens, its contacts close and give power continuity to 2A2 coil of contactor 2A, which then is free to be pulled in. Its timing can be set between 0.5 and 1.0 second as required. When the relay coil is de-energized, the relay allows its armature to release only when it has timed out.

45 The relay also controls the series brake operation during lowering. In lowering, if the controller is suddenly moved fast to its final position, this relay does not allow 2FA field weakening contactor to drop out until the relay has timed out. The 2FA2 coil of 2FA contactor gets its direct power over normally closed auxiliary contacts 2A4 of 2A contactor, which is controlled by the CR relay. Thus unless 2A contactor has pulled in, the 2FA contactor does not drop. This gives sufficient time for the brake to release.

50 *Relay AR—Accelerating relay*

This relay is similar to the CR relay. It controls 3A contactor both during hoisting and lowering to give proper sequence acceleration. It is set to time out in 0.5 second. Its coil gets de-energized when 2A contactor has pulled in.

55 *Relay DR—Decelerating relay*

This relay is similar to the AR relay. It is used in lowering direction only. It has two normally open contacts. It is connected across the field resistances 113—115 (points r1—r4). When 1FA contactor drops out during lowering, DR gets enough voltage to pull in. When pulled in, it gives direct power over its contacts to the coils 1E2 and 2E2 respectively of contactors 1E and 2E. When the master controller is suddenly brought to "off" position from the last notch, 70 where the lowering speeds are high, the relay

DR is automatically delayed in timing out. This permits contactors 1E and 2E to remain energized longer. The motion is thus automatically brought to slow speed by motor dynamic braking action, which is allowed to act for a longer time. When DR has dropped out, 1E contactor opens and 2E closes, and the series brake sets in. Thus the jerks on the crane hoist are reduced as the brake has to handle less energy, because the motion slows down sufficiently before the brake is released to hold the load.

Relay ALR—Accelerated lowering relay

This is the relay which has been introduced according to this invention. It is termed ALR i. e., accelerated lowering relay.

The relay has two independent coils fitted to the same magnetic core, indicated as ALR2 and ALR3. The coil ALR3 is connected across the resistance step points R1 and A i. e., combined steps 143-111. The second coil ALR2 is connected across the armature loop resistance step points R1 and B i. e., resistance 143 only. To provide for adjustment at site, the ALR2 coil is taken in series over a variable resistance (e).

The relay ALR is provided with a shunt magnetic circuit, which prevents the relay from pulling in again when heavy loads are being handled. A standard magnetic relay used for crane service with the above features is proposed, modified to give the characteristics described. The relay has one set of normally open contacts ALR1 which close when the relay is energized and is pulled in.

Operation of the relay ALR

When the motor is switched on, the current flows over the resistance steps 143 and 111 in the same direction. The voltages impressed on the two coils of the relay are therefore in the same direction. The relay is therefore pulled in instantly.

However, during lowering, when the load on the hook is overhauling i. e., when the load tends to drive the motor, the motor then becomes a generator. The current through the armature then reverses its direction, whereas the current through the series field circuit remains in the same direction. Thus the direction of current in the resistance step 143 is reversed i. e., the current flows from point B to point R1. The current through the resistance 111 still is in same direction, i. e., from point B to point A. As the motor becomes a generator, the field current now is supplied by its own armature. Depending on the load, therefore, the field current coming from the line and passing through resistance 111 back to the line is reduced. The effective voltage drop across the resistance step is reduced due to two opposing currents in the branches (B—A) and (R1—B). The voltage impressed on the ALR3 coil connected across points R1 and A is thus reduced, while the voltage across the ALR2 coil, across the points R1 and B is reversed. The relay thus becomes a differential compound relay. The effective voltage is therefore not able to hold the armature pulled in. Depending on the relay setting, the relay can be made to drop out on any overhauling load, even from the 2nd point of the master switch.

The relay thus works as a cumulative compound relay, during lowering for light loads, and differential compound relay for overhauling heavy loads. The values of resistance steps 111 and 143 being always in fixed ratio, a single

relay can be used for all motor sizes and for any desirable overhauling loads.

Function of relay ALR

- 5 The relay ALR controls the operation of the contactor 1A. Its normally open contacts are connected across the holding resistance of the coil of contactor 1A, shown as Resistance b in the control diagram. When the ALR is energized, the holding resistance is shorted over ALR1 contacts. The relay thus controls the operation of the contactor 1A.

- 10 Having thus explained the functions of various contactors and relays, the operation of the controller is explained briefly as follows. In the diagram only the points relevant to the description of the invention have been shown in order to make the explanation as simple and the diagram as clear as possible.

20

Hoisting cycle

- 25 As soon as the control power is put on by closing the main switch and the control knife switch, the power circuit becomes complete from the power line 1L over the contacts 1 of the master switch MC, over the operating coil M2 of the main contactor M to the negative power line 2L. The contactor M is energized and its main contacts M1 close. When M closes, its coil M2 gets permanently connected over its own auxiliary contacts M4, which also close when the coil is energized. The contactor M thus remains energized for all positions of the master switch MC. When the master switch is moved to the 1st position in the hoist direction, its contacts 3 engage with the segment 33 and thus get closed. This energizes the coil H2 of contactor H which closes its main contacts H1. Power then flows from the positive line 1L over the closed contacts H1, then passes over the trolley cross bar collector CB2, over the series coil SB of the electromechanical brake, through the series field SF, through the motor commutating field CF and the motor armature (ARM) over the trolley cross-bar collector CA2, through the resistance 14, then over the resistance step 111, over the main contacts M1, back to the negative line 2L. The motor is thus connected as a straight series motor over the control resistances and rotates in the hoisting direction as the series brake also gets energized and releases its holding shoes. To increase the motor speed, the master switch is moved further to points 2, 3, 4 and 5, which in sequence energize the contactors 2E, 1A, 2A and 3A allowing the control resistances 12, 14 and 111 to be shorted from the motor circuit. On the 5th point of the master switch, the motor gets connected directly on to the power lines 1L and 2L which gives the maximum hoisting speed.

- 60 *Lowering cycle.—Function of the relay ALR and contactors 1A and 4FA*

- 65 It is the object of my invention to design a circuit, which gives an automatic uniform acceleration of the crane hoist service during the lowering cycle, whatever the magnitude of the load handled by the crane, from empty hook to the maximum permissible overloads, without disturbing the stability of operation, i. e., without creating any run-away conditions inherent in the direct current series wound motor, when working with highly weakened fields at high speeds during lowering of heavy loads.

- 70 The invention lies in the control circuit design which is explained as follows:

(i) *Lowering with light loads*

Moving the master switch to the lowering direction, on the 1st point, contacts 2 engage with segment 22, and contacts 4 engage with segment 44 which makes the circuit to coils L2 and 1E2 of contactors L and 1E respectively. The contactors are thus energized and contacts L1 and 1E1 close. The current thus flows from the positive line 1L over the closed contacts L1, over the trolley crossbar collector SA1. After CA1, the current divides itself into two branches, one branch flowing along the point A1 through commutating field CF and the armature ARM and the resistances 14; while in the other branch, the current goes through the motor series fields SF, the brake coil SB and the resistances 11. At the point B, the branch currents combine together and flow over the resistance 111, and back to the negative line 2L over the main contacts M1 of the contactor M. Thus during lowering the motor armature and the motor series field are separately excited, connected in parallel, which gives the motor a shunt characteristic while lowering. In the series field circuit, the coils 1FA2, 2FA2 and 3FA2 of contactors 1FA, 2FA and 3FA remain energized over the master switch contacts 10, 11 and 12 as those master contacts remain engaged with their segments 100, 110 and 120. The current through the motor series field is thus limited by the resistances 112 and 111. The resistances are so selected that the motor field gets its full field current. The series brake also gets sufficient current to release its holding shoes instantly.

The contactors 1A, 2A, 3A and 2E are, however, not excited. The armature thus remains shunted over the resistance 12, points E1—E2, as 2E contacts remain closed. The armature circuit has therefore full resistance 14 in circuit. The voltage across the armature is such that the hook is lowered at a very slow speed, called creeping speed.

When the master switch is moved to 2nd point lower, its contacts 5 close, giving power to coil 2E2 of contactor 2E which pulls in and opens normally closed main contacts 2E1. The armature shunt circuit is thus opened, causing the motor to increase in speed.

When the master switch is moved to the 3rd point lower, its contacts 7 and 10 open and contacts 8 close. Contacts 10, which control the coil 1FA2 of contactor 1FA, thus break the power to that coil and the contactor 1FA drops out, which opens its main contacts 1FA1 in the series field circuit. This introduces resistance step 115 in series with the field; the field current is thus reduced, accelerating the motor further.

Master switch contacts 7 while opening de-energize the coil CR2 of relay CR. The contacts CR1 of the relay close after a time delay of about 0.75 second (which is the time setting of the CR relay). As the CR relay times out, its contacts CR1 close, giving circuit to the coil 2A2 of 2A contactor. As master switch contacts 8 close on the 3rd notch, 2A2 coil of contactor 2A is energized, because auxiliary contacts 1FA3 of contactor 1FA are already closed, 2A contactor pulls in closing its main circuit contacts 2A1. This short circuits the armature resistance step 142 giving higher voltage to the motor, which thus rises in speed still further. The contactors 1FA and 2A are so interlocked, that 1FA always opens first, after which 2A closes. Thus field is weakened first, after which the armature is strengthened to give rapid and smooth acceleration.

When the master switch is moved to 4th point lower, its contacts 6 and 9 close, while the contacts 11 open. Opening of master contacts 11, de-energizes the coil 2FA2 of contactor 2FA, because auxiliary contacts 2A4 of contactor 2A are already open. This opens 2FA1 main contacts in series field circuit, introducing resistance 114 in circuit. The field current is thus reduced, which accelerates the motor to the next higher speed step.

Closing of master switch contacts 9 gives connection to 3A2 coil of contactor 3A, which is also controlled by AR1 contacts of relay AR. As 2A contactor is already pulled in on the 3rd point of the master switch, its auxiliary contacts 2A3 which control AR2 coil of relay AR, open and de-energize the relay coil AR2. The relay AR then drops closing its contacts AR1, permitting 3A contactor to pull in. 3A1 contacts of contactor 3A when closed, remove resistance step 141 from armature circuit. The motor thus moves faster.

Closing of contacts 6 of the master switch gives power to coil 1A2 of contactor 1A, as the auxiliary contacts 2FA3 of contactor 2FA are already closed because 2FA contactor is open, and the auxiliary contacts 4FA3 of contactor 4FA are also closed as 4FA contactor remains energized. As motor is lowering light hook, the voltage drop across the resistance 111 due to the field current flowing through it is of such a value that the relay ALR remains energized with its contacts ALR1 closed. This permits the contactor 1A to close its main contacts 1A1. Once 1A contactor goes in, it is held in as the circuit is completed over the resistance b. Closing of 1A1 contacts of contactor 1A connects the motor directly to the main lines. However, in the field circuit, the resistances 143 and 111 get connected in parallel over 1A1 contacts. The resistances are so adjusted, that the series field has maximum resistance connected in series with it, while the armature is connected direct to the lines. This gives maximum lowering speed for light hook, depending on the resistance values selected. It should be noted that the contactor coil 4FA2 of contactor 4FA remains permanently energized, when 1A is energised and its auxiliary contacts 1A3 close, giving holding power to 4FA2 coil of the contactor 4FA.

50 (ii) *Lowering with heavy loads*

When there is overhauling load on the hook, the load begins driving the motor, which thus automatically becomes a generator, producing the counterbalancing dynamic braking action. When the magnitude of the load is sufficient, the relay ALR becomes a differential relay as explained before. When the load to be lowered is of the magnitude for which ALR relay is set to open, the relay ALR will get de-energized already on the 3rd point of the master switch and drop out, opening its contacts ALR1. The behaviour of the control up to 3rd point of the master switch is the same as for light hook duty. However, on the 4th point of the master switch, 3A contactor gets energized, but 1A contactor does not go in, because ALR1 contacts of the relay ALR are open which introduces the resistance b in series with the coil 1A2 which prevents the coil to have sufficient power to operate contactor 1A. At the same time, the auxiliary normally closed contacts of 3A4 of contactor 3A which give power to 4FA2 coil of contactor 4FA open out, when 3A contactor closes. As however 1A contactor also remains open which keeps its aux-

iliary contacts 1A3 to remain open. This opens out the power circuit of coil 4FA2 of contactor 4FA, which gets de-energized and drops out, closing its main normally closed contacts 4FA1. Closing of 4FA1 contacts then parallels the resistances 143 and 112. Thus the field is again weakened to its maximum value, however, the resistances are so adjusted that a stable full load lowering speed of between 180-200 per cent is obtained.

The values of the resistance steps can be given in per unit values. One per unit resistance is defined as the quotient of rated motor voltage divided by the rated full load motor current. Thus for light loads, total field resistance of 2.15 per unit can be introduced while for overhauling loads, that value becomes 1.83 per unit. For 230 volts, therefore, the total field current for maximum speed at light hook is about 45 per cent, and that for heavy overhauling loads is about 54 per cent. This would give about the same maximum hook speeds, both for light hook and full load on the hook.

Increased stability at lowering heavy loads

On overhauling loads, it is observed that 1A contactor does not go in, while 4FA contactor also drops out. It will therefore be observed that the resistance 111 becomes connected to the negative line, as a series resistance both to the armature and the series field.

With heavy loads on the hook, particularly on the last points of the master switch, the armature necessarily takes a heavy current; it supplies its own field current and also feeds current back into the line, the distribution of the current depending on the working conditions of the system at the time. The armature reaction therefore becomes more predominant and tends to weaken the motor field, which may produce an unstable condition at any time.

Addition of the series resistance in the line thus re-distributes the current distribution between the series field of the motor and the main power lines. It tends to force more current through the series field circuit and depending on the resistance value of resistance 111 in series with the main line, the current fed back to the power lines can be controlled during lowering of very heavy loads.

The armature reaction demagnetising effect is thus better counterbalanced by the series resistance in the line circuit, which increases the stability of motor operation at reduced field currents with heavy loads, by forcing more current through the series field as the load increases thus strengthening the generator counterbalancing action of the motor.

The main features of the control system herein described are thus given below:

(a) The main circuit as herein devised gives equal number of speed steps both in hoisting and lowering directions.

(b) The main circuit utilises the same number of contactor and relay devices, as in any other well-known system; however, the sequence of operation of the contactors is so adjusted that a contactor operates only once during a complete cycle of operation.

(c) The main circuit gives distinct resistance steps, both in armature and series field circuit, independent of each other. The resistances can thus be adjusted either in armature for hoisting speed adjustment or in series field for lowering

speeds adjustment, without one appreciably disturbing the other operation.

(d) The main circuit permits a straight forward control arrangement, where stability of operation is secured at each step without any control circuit complication.

(e) The main circuit gives always two armature closed-loop connections in the high speed operating points. This increases the security of

10 dynamic braking circuit, as the closed armature ring is always maintained even if one loop were to fail. This is obtained without any interlocking between contactors.

(f) The main circuit permits increased speeds 15 of the crane hoist uniformly from empty hook to heavy loads, without introducing any extra resistance step or extra contactor device.

(g) The main circuit permits increased stability of motor operation at high speeds with heavy 20 overhauling loads, by automatically adding a resistance in series with the line with overhauling hook loads.

(h) The relay ALR works automatically as compound additive relay, or as a compound differential relay, depending on the load on the hook of the crane hoist.

(i) The relay ALR serves for all the motor sizes, normally used for cranes up to maximum capacity.

30 (j) Relay ALR permits high lowering speeds both for light hook and heavy overhauling loads.

(k) The relay ALR gives maximum stability feature to the whole control while working at heavy overhauling loads by controlling a resistance in the main line circuit of the motor.

Having now particularly described and ascertained the nature of my said invention and in what manner the same is to be performed, I declare that what I claim is:

40 1. A magnetic controller for electrically operated travelling cranes employing an electrical circuit combining a direct current motor, a source of energy, and means of connecting the motor to operate as a series motor while raising a load, and connected to operate as a shunt motor while lowering a load, incorporating a shunt relay provided with two similar coils, one main operating coil connected to compare the algebraic sum of the voltage drops across a resistance in

50 the motor armature circuit together with a resistance connected to the main power line and in series with the parallel circuits formed by the motor armature and the motor field during lowering of the load, and the other coil to increase the sensitivity of the operation of the relay connected in series with a variable resistance, the two coils together being connected across the resistance in the motor armature circuit, the said shunt relay combining the two

60 coils operating as a compound relay during the hoisting of the load, and also during the lowering of a light non-overhauling load, and operating as a differential relay while lowering an overhauling load, the said relay being so connected that the same relay serves to control

65 motors of different horsepowers and ratings, the said relay being adapted to control two magnetic contactors, one contactor with normally open main contacts and the other contactor

70 with normally closed main contacts, the said two contactors controlling the speed regulating resistances in the armature and the field circuits of the motor, said resistances being so proportioned that the lowering speed with no-load on the hook becomes as high as the lowering speed

11

with full load on the hook, this operation of the contactors simultaneously adding a resistance in the main power circuit which diverts more current to the field of the motor thus automatically balancing the motor speed and increasing the stability of the motor, enabling the crane to handle the maximum overloads it is capable of, without any danger of the runaway conditions due to natural instability of a direct current mill type series motor under lowering conditions.

2. A control system for hoisting service employing a direct current motor connected to a source of energy and worked as a straight series wound motor while hoisting and as a shunt wound motor while lowering, including means for automatically controlling the regulating resistances over two contactors, one contactor having normally open contacts being connected across the combination of two resistance steps, one step being in the armature circuit and the other step being in series with the power line and the parallel circuit formed by the armature and the field during the lowering cycle; while the other of the two contactors, having normally closed contacts being connected between the resistances in the armature and the field, the said two contactors controlling the motor field current and the armature-back-electromotive force so as to give always maximum lowering speeds limited to the same values with the crane hook either empty or with full load hanging.

3. A control system for hoisting service employing a direct current motor connected to a source of energy and worked as a straight series motor while hoisting and as a weakened field shunt motor while lowering, providing a line resistance to be introduced automatically in series with the power line and the closed loop formed by the armature and the field combined, increasing the stability of a weakened field direct current motor handling heavy loads, the

5

12

said resistance being controlled by a contactor with normally open contacts, adapted to be introduced only during lowering of loads which are overhauling and being automatically shorted over the said contactor while lowering a light hook or a non-overhauling load.

4. A control system for hoisting service, combining a direct current motor, a source of energy, and means of connecting the motor to the source of energy to operate as a series-wound motor for raising a load and connected to operate as a shunt-wound motor for lowering a load, means for automatically varying the field strength of the motor when operating as a shunt wound motor to control the speed to the same maximum value when lowering a light hook as when lowering a full load on the hook, and simultaneously automatically introducing a resistance in series between the source of energy and the loop circuit formed by the motor armature and the motor field, and thereby increasing the stability of the motor even while lowering heavy overloads, and introducing during lowering a loop which is always closed in the armature circuit without any making or breaking contact points, and further automatically introducing a second dead closed circuit over normally closed contacts of a deenergized contactor, thus completely eliminating the chances of an open circuit in the armature loop which causes unmanageable over-speeding when heavy loads are lowered at high speeds.
